UNITED STATES PATENT OFFICE.

LORRAINE WINDSOR, OF CHICAGO, ILLINOIS.

DESIGN FOR WINDOW-DRAPERY.

43,398.

Specification for Design.

Patented Dec. 24, 1912.

Application filed October 9, 1912. Serial No. 724,850. Term of patent 3½ years.

To all whom it may concern:

Be it known that I, LORRAINE WINDSOR, a citizen of the United States, residing at Chicago, in the county of Cook and State of Illinois, have invented a new, original, and ornamental Design for Window-Drapery, of which the following is a specification, reference being had to the accompanying drawing, forming a part thereof.

The figure is a plan view of a window drapery, showing my new design.

I claim:

The ornamental design for a window drapery as shown.

LORRAINE WINDSOR.

Witnesses:

C. K. CHAMBERLAIN,
A. S. PHILLIPS.
